(57) **CLAIM**

The ornamental design for a mobile power supply unit as shown and described.

DESCRIPTION

1. Mobile power supply unit

1.1 : Front

1.2 : Back

1.3 : Left

1.4 : Right

1.5 : Top

1.6 : Bottom

1.7 : Perspective

1.8 : Perspective

View 1.1 is a front view of a mobile power supply unit showing my new design; view 1.2 is a rear view thereof; view 1.3 is a left side view thereof; view 1.4 is a right side view thereof; view 1.5 is a top view thereof; view 1.6 is a bottom view thereof; view 1.7 and view 1.8 are perspective views thereof.
